APPARATUS FOR CLEANING KNITTING MACHINES

John L. Allen, New Bedford, Mass.

Application August 21, 1946, Serial No. 691,946

5 Claims. (Cl. 66—168)

1

This invention relates to the cleaning of a machine such as used for knitting fabrics.

A knitting machine embodies a large number of small moving parts. Lint from the yarn used in knitting accumulates about these moving parts with the result that occasionally a bunch of yarn lint will be dislodged into some of the small moving parts so as to cause a breakage of the parts such as the needles. This requires the stopping of the machine for repair with the consequent loss of time and imperfect work.

One of the objects of this invention is to provide an apparatus for dislodging lint from the yarn which accumulates so that no build up of this lint can occur with the consequent dislodging of the lint and breaking of some of the small moving parts.

Another object of this invention is to provide a construction which may be easily assembled upon existing knitting machines so that the knitting machines that are already in use may be equipped with the apparatus.

Another object of the invention is to provide cleaning of both rotary and stationary parts with reference to which movement occurs by causing movement of the cleaning apparatus from one of the existing moving parts of the machine.

Another object of the invention is to provide a current of air for dislodging any lint and good sealing connections for the conduit for conducting the air to the desired parts.

Another object of this invention is to provide a relatively simple apparatus and one which may be maintained in operation without the necessity of providing a specially trained mechanic.

With these and other objects in view, the invention consists of certain novel features of construction, as will be more fully described and particularly pointed out in the appended claims.

In the accompanying drawings:

Fig. 1 is an elevation largely diagrammatic illustrating generally the parts of a knitting machine which enter into this invention;

Fig. 2 is a partial sectional view illustrating the supporting rod with my air chamber mounted thereon;

Fig. 3 is a sectional view on line 3—3 of Fig. 2;

Fig. 4 is a sectional view on a larger scale illustrating the moving parts of the knitting machine which are cleaned and the cleaning apparatus in its relation thereto.

In proceeding with this invention, I mount upon a stationary hollow rod which supports the upper structure of the machine, an air chamber, which air chamber is revolved by connection

2

with the spreaders for the work. From this hollow rod and the air chamber fixed and movable nozzles are arranged for sweeping air across the parts with reference to which movement occurs of the knitting machine. The source of air is supplied to some fixed point along the hollow rod for distribution to the nozzles.

With reference to the drawings, 10 represents the base plate of the machine which is supported on stanchions 11 above the annular frame 12 which is in turn supported by means of legs 13. Uprights 14 support the creel 15 carrying the packages of yarn 16 which are led upwardly to stop motion 17 and then downwardly through guides 18 and 19, the latter of which is supported by rod 20 centrally of the machine. The yarns are led through further guides 21 (see also Fig. 4) to the needles 22 which are carried by the rotating cylinder 23. These needles reciprocate in guides 24 in the cylinder as this cylinder is rotated by means of annular gear 25 engaging the driving pinion 26. This pinion is on the end of shaft 27 which has fixed and loose pulleys 28 and 29 engaged by a belt. A hand wheel 30 is also fixed on the shaft 27 for manual operation. A drive for feeding the knitted work 31 is taken from the other end of shaft 27 at 32 and transmitted as at 33 to pulley 34 and shaft 35 which engages and feeds the work downwardly of the machine in a known manner.

As the cylinder 23 is rotated vertical motion is transmitted to the needles 22 which have their looped portion 36 mounted between cams 37 and 38 mounted upon plate 39 which is secured to the base plate 10. The cams 37 and 38 are annular rings with spaced undulating surfaces to guide the portion 36 of the needle. A portion 40 of the plate 39 extends upwardly and has a ring 41 secured thereto which in turn carries a ring 42 supported by spring 43 and which may be adjusted against the spring by the V slot 44 in which the thumb screws 45 and handles 46 are mounted for engagement. This upper cam member 38 may thus be adjusted vertically and the proper spacing may be obtained between it and the cam edge of the cam 37.

The annulus 48 which is fixed to the frame of the machine carries a cam member 49 with which the sinkers 50 engage. The sinkers move with the cylinder 23 and are located between the needles 22 and are given a horizontal movement in and out by reason of their U shaped portion 51 which engages the cam 49. In order that lint will not collect between the needles and the sinkers or upon the cam member 49 which engages

the sinkers, air is directed to sweep these surfaces as will now be described.

The rod 20 is provided with a hollow center portion or bore 55 as shown in Fig. 2 and from this hollow center 55 an air nozzle 56 is directed so that as the needles and sinkers pass the end of this nozzle air will cause any lint which may have collected between them to be dislodged and blown outwardly of the machine. Air is supplied to this hollow portion 55 either by entry directly into the hollow portion 55 or by means of entry by the T connection 57 by means of a conduit 58 which leads to some suitable air supply source such for instance as a compressor or tank. Air under approximately 30 pounds pressure with an opening of about 20 thousandths of an inch at the nozzle is found to be a suitable proportion for the usual knitting machine.

In addition to the nozzle 56 I mount a chamber 59 upon the rod 20 externally of a hollow portion thereof so as to provide an annulus 60 about this rod. This chamber 59 is cylindrical with outwardly turned flanges 61 and 62 at either end with washer 63 mounted to telescope tube 20 and be sufficiently flexible so as to be responsive to pressure in the annulus 60 to force it against the rod while it also is provided with a flange to extend along the flanges 61 or 62 and be engaged by the caps 64 and 65 to bind it in position. This chamber 59 is prevented from axial movement along the rod by collars 66 and 67 held by set screws 68 and 69 upon the rod 20. An opening 70 is provided in the wall of the rod 20 to communicate the bore 55 of the rod with the annulus 60. Nozzle 71 is rigidly mounted upon the chamber 59 to extend directly toward the fixed cam 49 so that the discharge of air from this nozzle as it is rotated will sweep the cam 49 and keep its surface free of lint.

In order to rotate the chamber 59 and its nozzle 71 a bracket 72 is mounted upon the chamber and is provided with a pin 73 (see Fig. 4) and the knurled handle 74 to extend downwardly and lock with the rotating spreader 75 which serves as a guide for spreading the work 31 as it is formed and is turned by the machine.

By this arrangement, I provide a fixed nozzle past which the needles and sinkers move and also a rotary nozzle which is swept across the stationary parts of the machine so that between these nozzles all lint from moving parts where it freely accumulates is dislodged and the breakage due to the accumulation of lint and fine particles is reduced or eliminated.

I claim:

1. Apparatus for cleaning a knitting machine of the type having a stationary part and a cylinder rotating relative to the same, comprising a hollow supporting rod within said cylinder, a chamber rotatably mounted on said rod, a nozzle carried by said chamber and rotatable therewith, means on said chamber to engage a rotatable part of said machine for rotation of said chamber, a conduit from said hollow rod to said chamber and a conduit from said rod to some external part of the machine for conducting air to said hollow rod.

2. Apparatus for cleaning a knitting machine of the type having a stationary part and a cylinder rotating relative to the same, comprising a hollow supporting rod within said cylinder, a chamber rotatably mounted on said rod, a nozzle carried by said chamber and rotatable therewith, means on said chamber to engage a rotatable part of said machine for rotation of said chamber, a conduit from said hollow rod to said chamber and a conduit from said rod to some external part of the machine for conducting air to said hollow rod, and a second nozzle extending from said hollow rod and fixed therewith.

3. Apparatus for cleaning a knitting machine of the type having a stationary part and a cylinder rotating relative to the same, comprising a hollow supporting rod within said cylinder, a chamber rotatably mounted on said rod, a nozzle carried by said chamber and rotatable therewith directed toward movable mechanism in the stationary part, means on said chamber to engage a rotatable part of said machine for rotation of said chamber, a conduit from said hollow rod to said chamber and a conduit from said rod to some external part of the machine for conducting air to said hollow rod.

4. Apparatus for cleaning a knitting machine of the type having a stationary part and a cylinder rotating relative to the same, comprising a hollow supporting rod within said cylinder, a chamber rotatably mounted on said rod, a nozzle carried by said chamber and rotatable therewith, means on said chamber to engage a rotatable part of said machine for rotation of said chamber, a conduit from said hollow rod to said chamber and a conduit from said rod to some external part of the machine for conducting air to said hollow rod, and a second nozzle extending from said hollow rod and fixed therewith and directed toward movable mechanism in said movable part.

5. Apparatus for cleaning a knitting machine of the type having a stationary part and a cylinder rotating relative to the same, comprising a hollow supporting rod within said cylinder, a chamber rotatably mounted on said rod, a nozzle carried by said chamber and rotatable therewith directed toward movable mechanism in the stationary part, means on said chamber to engage a rotatable part of said machine for rotation of said chamber, a conduit from said hollow rod to said chamber and a conduit from said rod to some external part of the machine for conducting air to said hollow rod and a second nozzle extending from said hollow rod and fixed therewith and directed toward movable mechanism in said movable part.
